UNITED STATES PATENT OFFICE.

HUGO PICK, OF WINNETKA, ILLINOIS, ASSIGNOR TO ALBERT PICK & COMPANY, OF CHICAGO, ILLINOIS, A CORPORATION OF ILLINOIS.

DESIGN FOR A SPOON OR SIMILAR ARTICLE.

Application filed November 28, 1921. Serial No. 518,460. Term of patent 7 years.

To all whom it may concern:

Be it known that I, Hugo Pick, a citizen of the United States, residing at Winnetka, in the county of Cook and State of Illinois, have invented a new, original, and ornamental Design for a Spoon or Similar Article, of which the following is a specification, reference being had to the accompanying drawing, forming a part thereof.

In the drawing: The figure is a plan of a handle showing my new design.

The design is characterized in having a slightly sloping and bevelled margin A and a hammered face B within the bevelled margin.

I claim:

The ornamental design for a spoon or similar article, as shown and described.

HUGO PICK.
